Inventor:

Samuel C. Hunter

United States Patent Office.

SAMUEL C. HUNTER, OF EAST HICKORY, PENNSYLVANIA.

Letters Patent No. 71,488, dated November 26, 1867.

IMPROVEMENT IN SEED-PLANTERS.

The Schedule referred to in these Letters Patent and making part of the same.

TO ALL WHOM IT MAY CONCERN:

Be it known that I, SAMUEL C. HUNTER, of East Hickory, in the county of Forrest, State of Pennsylvania, have invented a new and improved Seed-Planter; and I do hereby declare that the following is a full and exact description thereof, reference being had to the accompanying drawings, and the letters of reference marked thereon.

Figure 4 shows my machine complete from the rear of the same.

A A are the wheels. B B are the false wheels, fastened to the wheels A A by means of the clasps U U U, as seen more fully in fig. 2. C C are the dropping-boxes. D D and E are the levers, by means of which the dropping-boxes C C are drawn together, as shown in fig. 4, so as to put the machine out of gear, by taking the dropping-pins Q Q away from the eccentrics N N N, (seen more fully in figs. 2, 3, and 6,) allowing the wheels to turn without operating the droppers. F is a solid standard, fastened to the axle O, upon which the lever E is fastened by means of the turning-bolt f. The lever E passes up in front of the seat K, where it can be easily worked by the operator. G is a clasp to keep the lever E in place. H is an iron staple fastened in G, by means of which a roller may be attached, if desired. I I are handles to the covering-ploughs P P, which pass through the clasps T T T T, and come within reach of the seat K, where they can be raised or lowered by the operator, as desired. J J are the legs to the seat K. L L are funnels, leading to the grain-receiver a, as seen in figs. 3 and 16. M M are hinges, by means of which the dropping-boxes C C are hung to the axle O. N N N N are the eccentrics, which are seen more fully in figs. 2 and 3. O is the axle on which the wheels revolve. P P are the covering-ploughs, and are fastened to the handles I I in such a manner as to follow immediately after the dropping-boxes C C so as to cover up the seed. Q Q are the dropping-pins, which are connected with the dropper V, (seen in fig. 3,) and work upon the eccentrics N N N N.

Figure 1 shows my machine with one wheel off, and the lever E set, thereby showing the machine in gear. This view is also a rear view.

Figure 2 shows an inside view of one of the wheels, in which A is the wheel itself.

B is the false wheel, to which the eccentrics are attached. N N N are the eccentrics. This wheel B is a flange-wheel, and is seen more fully in fig. 7. U U U are clasps, the shape of which is seen in figs. 9 and 10. These clasps are bolted to the wheel A in such a manner as to fit loosely on the flange of the false wheel B, so as to allow the same to be turned easily by the hand, so the wheel can be placed in such a position as to bring the eccentrics opposite those on the other wheel, so that both droppers will be worked at the same time. This is necessary on account of the eccentrics getting out of position in turning the machine around. d is a catch, which fits in the notches e e e to prevent the false wheel B from being revolved by the friction of the dropping-pins Q Q on the eccentrics N N N. These notches are seen more fully in Figure 6, which is a transverse view of the false wheel B.

Figure 7 is an end view of the false wheel B.

Figure 5 is a top view of my machine, showing the wheels A A, false wheels B B, axle O, seat K, funnels L L, plough-handles I I, and the clasps T T, the lever E and its clasp G, and the seat-beams J J.

R is a catch, which holds the lever E so as to prevent the machine from getting out of gear. This is worked by the foot of the operator. S is the pole.

Figure 3 shows a side view of my machine, with the wheel nearest removed. This figure shows the wheel A, false wheel B, dropping-box C, with one side removed showing the internal arrangement of the same, the axle O, plough P, plough-handle I, clasps T T, staple H, funnel L, seat K, seat-beam J, eccentrics N N, clasps U U U, pole S.

Figure 16 shows the internal construction of the dropping-box C, the same as seen in fig. 3, in which a is the seed-box.

V is the dropper. Q, the dropping-pin, which passes out through the slant e, shown in Figure 15, to the eccentrics N N N on the wheel B. X is a notch, cut in the side of the dropper, shown more fully in figs. 11 and 13.

Figures 11 and 13 also show the dropping-pin more perfectly.

Y is a shelf, forming the bottom of the seed-box a. Z is a leather valve, which presses against the dropper V. The dropper is held up to the position shown in this (16) figure by means of an elastic strap, W, shown in

fig. 13. When the wheel revolves, one of the eccentrics pulls down the dropper V by means of the dropping-pin Q, the leather valve slides along it and prevents any of the seeds from escaping, except what are lodged in the notch X, which fall down through the space b to the earth, and are covered by the ploughs P P. As soon as the dropping-pin Q slips off the eccentric N N, it is brought back to its position by the elastic strap W, and waits to be carried down by the next eccentric.

Figure 13 shows this dropper V in an inverted condition, showing the elastic strap W.

The strap W is also shown in Figure 12, which is a back view of the dropper V, and also an inverted one.

Figure 11 is also an inverted view of the dropper V, but a front one showing the notch X, and also the dropping-pin Q.

Figure 14 is a bottom view of the dropper V, showing the attachment of the elastic strap W, the other end of which is attached to the top of the dropping-box C, as seen in fig. 3, where the dropper is shown as pushed down by the dropping-pin on the eccentric.

Figure 9 is a side view of the flange-clasp U, and

Figure 10 a bottom view of the same.

The funnels L L are seen in figs. 1, 3, 4, and 5. These are placed in holes bored through the axle O, so as to fill the seed-boxes a a. These funnels are removable at the pleasure of the operator.

This seed-planter can be used for both large and small grain, by varying the size of the notch X in the dropper V. This notch X or pocket is on a separate block, and fastened to the dropper by means of a dovetail slide.

What I claim as my invention, and desire to secure by Letters Patent of the United States, is as follows, to wit:

I claim the construction of a seed-planter, with the dropping-boxes C C constructed as described, in combination with the lever E and the eccentrics N N N, and the false wheel B and the covering-ploughs P P, when the same are constructed as described, in the aforesaid combination, for the purposes set forth.

SAMUEL C. HUNTER.
